UNITED STATES PATENT OFFICE.

THOMAS GALLIGAN, OF BRADFORD, OHIO, ASSIGNOR OF ONE-HALF TO
JOHN G. PORTER, OF SAME PLACE.

CAR-COUPING.

SPECIFICATION forming part of Letters Patent No. 567,465, dated September 8, 1896.

Application filed April 3, 1896. Serial No. 586,067. (No model.)

To all whom it may concern:

Be it known that I, THOMAS GALLIGAN, of Bradford, in the county of Miami and State of Ohio, have invented new and useful Improvements in Car-Couplings, of which the following is a full, clear, and exact description.

This invention relates to car-couplings of the Janney type, in which a drawhead having a pivoted laterally-movable knuckle is provided.

The object of the invention is to provide a car-coupling of the indicated character with novel features of simple construction, which will render the improved coupling very effective in operation and adapt it for release from another coupling of similar construction in a safe manner from the side of the car having the improvements.

The invention consists in the construction and combination of parts, as is hereinafter described, and pointed out in the claims.

Reference is to be had to the accompanying drawings, forming a part of this specification, in which similar characters of reference indicate corresponding parts in all the figures.

Figure 1 is a reverse plan view of two main portions of two car-couplings having the improvements, and of a car-frame portion shown in dotted lines, one coupling being represented in place thereon. Fig. 2 is a detached and partly-sectional plan view of the main portion of the improved car-coupling. Fig. 3 is a front end view of the improved coupling. Fig. 4 is a detail view.

In carrying into effect the features of invention, 10 indicates the novel draw-head, which is integral with the elongated draw-bar 11, the latter being in service secured to the frame A of a car by any preferred means. The draw-head 10 projects at one side of the draw-bar and is forwardly curved a suitable degree, having a convex outer side and a concave front produced thereon, which converge and afford a horn a. The draw-head is chambered, so as to provide a receptacle for the tailpiece 13 of the knuckle 12, and the upper and lower sides of said chamber b are rendered level and parallel, so that the tailpiece may freely rock therein, the chamber having an opening c at the front and side opposite

from the horn a for the free introduction of the tailpiece, said opening being shown in Fig. 2.

The tailpiece 13 is of a thickness that will permit it to loosely fit in the chamber b, and has a curved edge portion d formed on it, which is concentric with the pivot-hole formed in the tailpiece for the reception of the pintle-bolt 14, said hole being in alignment with opposite perforations of equal diameter therewith, which are produced at a correct point in the upper and lower walls of the draw-head chamber. There is a toe 13^a formed integral with the tailpiece 13, which toe projects therefrom, having suitable length and breadth to adapt it for effective service, and between the forward edge of the toe and a shoulder e, where the thicker knuckle-body 12 integrally joins the tailpiece, the peripheral portion g of the latter is convexly curved, and its arc may be concentric with the convex-curved edge portion d.

The knuckle-body 12 and its integral latching-jaw 12^a are preferably made equal in thickness with that of the draw-head 10, and said parts are laterally curved to produce a hook-like formation, the jaw being rendered substantially ovate edgewise and curving slightly rearward when in a normal position, so as to insure its latching engagement with a similar jaw on a mating car-coupling and maintain such a connection until designedly released. It will be seen that, the width provided for the knuckle-body 12 at its shoulder e being less than the transverse diameter of the tailpiece 13, an opening for the limited rocking movement of the knuckle-body is afforded at the rear edge of the latter, where it joins the tailpiece. It is essential that such a relative proportion be had with regard to the construction of parts just described as will permit a sufficient rocking movement of the knuckle-jaw 12^a for its release from a coupled condition, as will be more fully explained. The knuckle-block 12 is furnished with a laterally-extending limb 12^b, which projects nearly opposite from the latching-jaw 12^a and has an oblong orifice i formed in it, which extends across the limb, as indicated by dotted lines in Figs. 1 and 2. An arm 10^a is formed on the draw-head 10

near its junction with the draw-bar 11, said arm projecting at the same side of the coupling with the limb 12^a. On the outer end of the arm 10^a there is a spring carrier-rod 15, 5 pivoted by its rear end, as at *k*, the free front end of said rod loosely passing into the orifice *i* of the limb 12^b.

The carrier-rod 15 is furnished with a collar *m*, that is formed or secured thereon near the 10 point of its pivotal connection with the arm 10^a. A strong spiral spring 16 is mounted on the carrier-rod 15, having such a length as will permit its ends to respectively press on the collar *m* and on the rear side of the 15 limb 12^b, thereby normally effecting a contact of the toe 13^a with the rear wall of the draw-head chamber *b*, as shown in Fig. 2, which will give to the latching-jaw 12^a a correct position for a coupling engagement with 20 a similarly-positioned jaw on a car-coupling of like construction. On the outer end of the limb 12^b a link-bar 17 is pivoted, the other end of said link, that trends toward the car-frame A, having a pivotal connection with 25 one end of the lever 18. As shown in Fig. 1, the lever 18 is laterally bent to adapt it for efficient service, and at a suitable distance from the pivoted connection *n*, between the lever and link-bar, the lever is pivoted 30 on the car-frame A, as represented at *o*. A sufficient length is provided for the main portion of the lever 18 to extend its free end 18^a near to the side of the car-frame, so that said end may be safely manipulated as a handle by an operator alongside of the car. The 35 portion of the lever 18 that is between the pivot *o* and free end 18^a is preferably supported by the bracket-plate 19, that is in the form of a bent bar having its ends secured to the car-frame and so offsetted between these points of attachment that the long member of the lever will be adapted for vibration while resting on the bracket-plate.

The bracket-plate 19 is provided with a 40 looped projection *p* on its lower side, that is located at a point which will permit the longer member of the lever 18 to slide under a spring *p'*, that is secured above the loop, and be located therein by return of the spring *p'*, 45 this provision being made to enable the holding of the knuckle open when it is necessary to avoid coupling with another, the release of the lever being readily effected in an obvious manner. It will be seen that by the 50 provision of the lever 18 and link 17 convenient and reliable means are afforded for the outward and rocking movement of the knuckle 12, against the stress of the spring 16, to release two couplings that are on cars 55 and have coupled engagement with each other, so that a disconnection of two coupled cars may be safely and conveniently effected.

The latching-jaw 12^a is caused, when in normal position, to project its nose one-half 60 of the length of said jaw across a straight line that extends longitudinally through the transverse center of the draw-head 11, so that

the center of the draft strain applied to two coupled draw-heads on two of the improved car-couplings will be represented by a line 70 11, that crosses the centers of the pivot-bolts 14 and transverse centers of the latch-jaws 12^a and draw-bars 11, as clearly shown in Fig. 1.

The manner of constructing the knuckle 75 and chambered draw-head insures the release of the knuckle-block in case the pivot-bolt 14 should be detached or broken, and as the link 17 is still in connection with said knuckle it will be evident that the latter will be prevented from falling on the ground, whereby it is saved from loss or from producing an accidental derailment of cars, that might occur if this part of the coupling should fall on one of the track-rails. 80

It will be evident that in the improved car-coupling there is no need to provide means for locking the knuckle in closed adjustment, as the application of draft force to two of said 85 couplings that are connected being central on the line 11 insures a maintenance of their coupled condition at all times until one or both of the knuckles are laterally swung on their pivot-bolts to uncouple the draw-heads.

It will be apparent that the stress of the 90 springs 16 holds the mating jaws 12^a in position for an automatic coupling engagement when two of the improved car-couplings are brought together, the convex and rearwardly-sloping faces of the front sides of their hooked 95 members facilitating a latching connection of said parts. The hook nose of the latching-jaw 12^a is horizontally slotted at its center of thickness, as shown at *r* in Fig. 3, and said nose is also vertically perforated, as at *s*, for 100 the reception of an ordinary coupling-pin, (not shown,) so that a common coupling may be connected by its elongated link with the 105 improved car-coupling if the link is placed in the slot *r* and then secured by a pin dropped into the perforations *s*.

Having thus described my invention, I claim as new and desire to secure by Letters Patent—

1. The combination with a chambered draw-head, and a pivoted knuckle having a hook-like latching-jaw and a lateral projection opposite said jaw; of a rod pivoted to said draw-head and supporting a spring adapted to hold said jaw in coupled engagement, the free end 115 of said rod passing through said projection, a lever fulcrumed on the car-frame, and a link pivoted to said projection and to said lever, as specified.

2. In a side-latching car-coupling, the combination with the chambered draw-head having an arm extending therefrom, and a knuckle having a hook-like latching-jaw pivoted in said draw-head, of a rod pivoted to said arm, and carrying a spring adapted to 120 normally hold said knuckle in closed adjustment, and means for opening said jaw against the action of said spring, as specified.

3. In a side-latching car-coupling, the com-

- bination with a chambered draw-head having an opening therein at the front and near one side of the chamber; of a knuckle having a hook-like latching-jaw, a tailpiece integral 5 with said knuckle concentrically pivoted in said opening, said tailpiece being provided with a toe adapted to limit the closure of said latching-jaw, and a rod pivoted to an arm projecting from said draw-head and supporting a spring adapted to keep said toe normally in contact with the rear wall of the draw-head chamber, as specified.
4. In a side-latching car-coupling, the combination with a draw-head having an arm extending therefrom, of a knuckle pivoted in said draw-head provided with an integral hook-like latching-jaw and tailpiece, a limb extending laterally from the rear side of said knuckle having an orifice therein, and a 15 spring-encircled rod pivoted at one end on said arm, its other end passing through said orifice, the tension of the spring normally pressing said arm and said limb apart, as and for the purpose specified.
- 20 5. In a side-latching car-coupling, the combination with a draw-bar, a draw-head thereon having a chamber open partly at the front, and an arm laterally projected therefrom near the draw-bar, of a knuckle-block having a hook-like latching-jaw, and provided with a lateral limb which is transversely perforated, a carrier-rod pivoted on the end of the arm 25 and loosely engaging the perforation of said limb, a spring on said carrier-rod adapted to press the latching-jaw partly across the median line of draft force applied to the coupling, a link pivoted to the limb and also to the end of a bent lever that is fulcrumed on the car-frame, and a bracket-plate on said frame adapted to retain the lever when the latter is rocked, to hold the knuckle open, as specified. 35
6. In a side-latching car-coupling, the combination with a chambered draw-head, and a knuckle pivoted therein having a hook-like latching-jaw and an integral tailpiece, said tailpiece being provided with a toe adapted to limit the closure of said latching-jaw, of a laterally-extending arm formed on said draw-head at its rear, a laterally-extending limb 40 formed on said knuckle having an oblong orifice therein, a rod pivoted at one end on said arm, its other end passing loosely through said orifice, a spring encircling said rod arranged to normally force said rod out of said orifice 45 and keep said toe in contact with the rear wall of the draw-head chamber, and means for counteracting the action of said spring, as specified. 50
